UNITED STATES PATENT OFFICE.

PETER WILHELM ZIEGLER, OF CANNSTADT, GERMANY.

SIDE STEEL FOR CORSETS.

SPECIFICATION forming part of Letters Patent No. 626,957, dated June 13, 1899.

Application filed December 21, 1898. Serial No. 699,907. (No model.)

To all whom it may concern:

Be it known that I, PETER WILHELM ZIEGLER, a citizen of the Empire of Germany, residing in Cannstadt, in the Kingdom of Würtemberg, in the Empire of Germany, have invented certain new and useful Improvements in Side Steels for Corsets, of which the following is a specification.

This invention has reference to improvements in side steels for corsets; and the invention consists of a side steel for corsets comprising two superposed strips of spring-metal, one of said strips being provided near one end with side recesses, forming a contracted portion or neck, said recessed portion of the strip being guided in the slot of the other strip; and the invention consists, further, of a side steel for corsets comprising two superposed strips of spring metal, each of said strips being provided near one end with a longitudinal slot and near the opposite end with side recesses, forming a contracted portion or neck, the recessed portion of each strip being guided in the slot of the other strip.

In the accompanying drawings, Figure 1 represents a portion of a corset with my improved side steels applied thereto. Figs. 2 and 3 are plan views of the individual strips of which my improved side steel is composed. Figs. 4 and 5 are respectively a plan view and a side view of said two strips as interlocked to form the completed side steel. Figs. 6 and 7 are plan views of the strips of a simplified form of side steel embodying my improvement, and Figs. 8 and 9 are respectively a plan view and a side view of the two strips shown in Figs. 6 and 7 as interlocked to form the completed steel.

Similar letters of reference indicate corresponding parts.

My improved side steel for corsets is composed of two superposed strips *a* and *b* of spring metal, said strips being joined together, so as to be capable of movement one upon the other, whereby the flexibility of the complete side steel is considerably increased and the risk of breaking considerably reduced as compared with side steels consisting of a single thickness of metal.

In order to join the two strips *a* and *b* together in such a manner as to permit a sufficient amount of longitudinal movement between said strips when so joined, a slot *b'* is formed in one end of each of said strips, and the opposite end is provided with side re-

cesses which form a contracted portion or neck *a'* at said opposite end of the strip, as shown in Figs. 2 and 3. The two strips *a* and *b* thus provided with slots and recesses are fitted together by passing the recessed end of one strip 60 through the slot in the opposite strip until the contracted portion *a'* is located in said slot and then passing the recessed end of the second strip through the slot of the first strip until its contracted portion is located in the said 65 slot of the first strip. The two strips are thus interlocked, so as to form the complete steel, as shown in Figs. 4 and 5. They are capable of sliding movement upon each other, which may take place when the steel is bent, the 70 parts *a'* and *b'* serving to guide the strips.

Instead of supplying both ends of the strips with side recesses and slots, if preferred this connection may be employed at one end only, as in Figs. 6 to 9, leaving the other ends of 75 the strips free.

The completed steel may be fixed in position in the garment in any suitable manner.

The strips are preferably of unequal length, 80 as shown in the drawings.

Having thus described my invention, I claim as new and desire to secure by Letters Patent—

1. A side steel for corsets, consisting of two superposed strips of spring metal, one of said 85 strips being provided at some distance from one end with a longitudinal slot, and the other strip being provided at some distance from one end with side recesses forming a contracted portion or neck, said recessed portion of 90 one strip being guided in said slot of the other strip, whereby said strips are interlocked at one end, the opposite ends of said strips being disconnected from each other, substantially as set forth. 95

2. A side steel for corsets, consisting of two superposed strips of spring metal, each of said strips being provided near one end with a longitudinal slot and near the opposite end with side recesses forming a contracted portion or neck, the recessed portion of each strip being guided in the slot of the other strip, substantially as set forth. 100

In testimony that I claim the foregoing as my invention I have signed my name in presence of two subscribing witnesses.

PETER WILHELM ZIEGLER.
